PISTON CONSTRUCTION

Joseph F. Bleser, Springfield, Ill.

Application July 24, 1931. Serial No. 552,855

9 Claims. (Cl. 309—4)

This invention relates to pistons and particularly to double-end pistons intended for use in engines of the cam or swash-plate type, where in a cam or plate of suitable form is secured to the engine shaft and operatively related to a plurality of pistons positioned around the shaft in a manner to be driven thereby when the pistons are moved longitudinally in their respective cylinders.

10 One object of the present invention is to provide a piston having anti-friction means associated therewith and having means for securing the anti-friction means against relative movement with respect to the piston.

15 Another object of the invention is to provide a piston having a plurality of anti-friction members mounted in and spaced longitudinally of the piston, and having means directly associated with the supporting means of the anti-friction members for securing and retaining the members in fixed relative position with respect to each other.

20 A further object of the invention is to provide a piston formed of a plurality of relatively adjustable aligned parts or members having anti-friction thrust devices mounted in the respective members, and wherein adjustable means are provided for securing the respective members together and for directly connecting said anti-friction devices to each other.

25 A still further object of the invention is to improve devices of the character described in sundry details hereinafter referred to and particularly pointed out in the appended claims.

30 One embodiment of the present invention is shown for illustrative purposes in the accompanying drawing in which,

Fig. 1 is a longitudinal sectional view of a piston embodying features of the present invention;

40 Fig. 2 is a fragmentary longitudinal sectional view taken on the line 2—2 of Fig. 1; and

Fig. 3 is a transverse sectional view of the piston taken substantially as indicated by the line 3—3 of Fig. 1.

45 The present invention is an improvement on the piston construction described and claimed in my copending application filed December 15, 1930, Serial No. 502,429, and the type of engine to which the present invention is particularly adapted for use is fully described in my copending application filed October 20, 1928, Serial No. 313,901, the said engine being of the cam type in which a rotatable engine shaft is mounted in frame members, and is provided with a cam adapted to be operatively related to a plurality

of pistons mounted in cylinders formed in the frame members and annularly spaced around the engine shaft.

Referring to the drawing of the illustrative embodiment of the present invention, my improved piston, designated as a whole by the numeral 8, contemplates a plurality of aligned end portions or members 9 and 10 of substantially like construction adapted to be positioned end to end as shown in Fig. 1 in the drawing, and to be secured together by means of bolts 11 provided with screw threaded nuts 12 adjacent their end portions for drawing the members 9 and 10 toward each other, the members 9 and 10 being provided with hand holes 13 by which access to the nuts 12 may be obtained for the purpose above described.

The end members are of substantially hollow construction as shown in Figs. 1 and 2 of the drawing, thereby contributing to their lightness, the outer ends of the pistons being strengthened by means of ribs 14 extending transversely across the interior of the piston heads. The end members 9 and 10 are each provided with anti-friction rollers 16, the rollers being suitably spaced from each other adjacent the inner ends of the members 9 and 10 and adapted to receive the rim of a cam 17, a fragment of which is shown positioned between the rollers 16 in Fig. 1 of the drawing, the rollers 16 engaging opposed faces of the cam 17 in a manner to rotate the cam and shaft on which it is mounted when the pistons are moved longitudinally of their respective cylinders under the influence of an explosion or pressure within the head of the cylinders as is common practice in engines of the type above referred to.

To permit of the arrangement above described, one side of the members 9 and 10 adjacent their inner ends is cut away as indicated at 18, thereby providing a recess in one side of the piston whereby the periphery of the cam 17 may intersect the periphery of the piston and permit suitable engagement of the rollers 16 with the opposed faces of the cam.

In the construction shown, each of the rollers 16 comprises an annular member having a channel 19 formed in its inner side, and suitably positioned within the annular member is a retainer 20 having a plurality of annularly spaced radially disposed apertures 21 formed therein adapted to receive rollers 22 in a manner to permit one side of the rollers to extend into the channel 19, and the opposite side of the rollers to protrude inwardly from the inner face of the

retainer 20. Thus it will be observed that the annular member or roller 16 provides an outer race for the rollers 22.

Positioned within the rollers 22 is a bearing 5 cone 23 having an outwardly extending annular flange 24 at one end adapted to engage one of the ends of the rollers 22, and at the opposite end of the cone is a ring 25 adapted to engage the opposite ends of the rollers 22.

10 For supporting the anti-friction rollers 16 and their bearings in the piston members 9 and 10, respectively, hollow shafts 26 and 27 are positioned within the cones 23 and rings 25 and suitably mounted in bosses 28 and 29 formed 15 respectively on the members 9 and 10 of the pistons.

For varying the distance between adjacent faces of the rollers 16 in a manner to provide efficient cooperative relationship between the 20 rollers 16 and the opposed faces of the cam 17, a plurality of shims 30 are positioned between the adjacent ends of the members 9 and 10 and held in place by the bolts 11 passing through apertures formed in the shims. Thus it will 25 be observed that by adding or removing one or more shims, the space between adjacent faces of the rollers 16 may be varied to properly position them with respect to the cooperating faces of the cam 17.

30 In the actual operation of devices of the character above described, it has been found that tremendous force or thrust is exerted between the cam 17 and rollers 16, and that owing to the inertia of the piston structure, particularly 35 at the ends of its stroke, there is grave danger of breaking or rupturing one or the other of the piston members 9 and 10 when the cam 17, in certain stages of its operation, exerts a force to reverse the direction of movement of the 40 piston structure.

Owing to the desirability of maintaining a suitable degree of lightness in the piston members 9 and 10, it is difficult to obtain a desired degree of strength in these members without adding an 45 undesirable amount of material to the members, thereby increasing their weight and inertia.

To obviate the necessity of adding material to the members 9 and 10, and to relieve the members from a considerable portion of the strain 50 or force exerted by the cam 17 against the rollers 16, and at the same time obtain a desirable degree of strength in the piston structure as a whole, I provide a tie rod 31 adapted to connect the hollow shafts 26 and 27 of the respective 55 anti-friction rollers 16 securely together, and also adapted to be positioned closely adjacent the rollers 16 in a manner to most effectually receive the strain exerted thereon by the cam 17.

In the present arrangement, one end of the 60 tie rod 31 extends through an aperture 32 formed in one of the bosses 29 of the member 10 and through an aperture 33 formed in the hollow shaft 27, the said end of the rod 31 within the shaft 27 being screw threaded and provided with a shoulder 34 against which a threaded nut 35 may be positioned, and, if desired, a spacing washer 36 may be positioned between the nut 35 and the inner face of the hollow shaft 27.

The opposite end of the tie rod 31 extends 70 through an aperture 37 formed in one of the bosses 28 of the member 9 and through an aperture 38 formed in the hollow shaft 26, the said opposite end of the tie rod 31 being screw threaded to receive a nut 39 which may be drawn 75 down tightly against a spacing washer 41 po-

sitioned between the nut and the inner face of the hollow shaft 26, thereby serving to draw the hollow shafts 26 and 27 toward each other and to retain the shafts and associated anti-friction members against relative displacement with respect to the piston members 9 and 10 and with respect to each other, it being understood that when the nut 35 is brought into engagement with the shoulder 34, the tie rod 31 may be held 80 against rotation while the nut 39 at the opposite end of the rod may be drawn down as tightly as may be found desirable, and locked against accidental displacement by a cotter pin 40 or other suitable securing means.

It will be observed that when shims, such as those designated by the numeral 30 are added or removed to provide proper adjustment between the cam 17 and inner or adjacent faces of the rollers 16, the nut 39 by reason of its screw-threaded connection with the tie rod 31 provides suitable adjusting means for securing the hollow shafts 26 and 27 together regardless of whether more or less shims are positioned between the adjacent ends of the piston members 9 and 10.

In practice, the anti-friction rollers 16 and cam 100 17 are relatively adjusted with respect to each other in a manner to provide the least possible clearance between the cam and rollers at all times, thereby avoiding a pounding action between the rollers and cam when the movement of the piston 105 is reversed, and under such circumstances, it will be observed, from the foregoing description, that when a force or thrust is exerted by one side of the cam 17, for example, against the roller 16, mounted on the hollow shaft 27, the force, instead of being transmitted to the piston member 10, will be taken up by the tie rod 31 owing to its connection with the hollow shaft 26 on which the other anti-friction roller 16 is mounted and which bears against the opposite side of the cam 17. 110 Thus, it will be noted that the force or thrust exerted on one of the rollers 16 instead of being transmitted to its associated piston member will be resisted by the opposite working face of the cam through the anti-friction roller associated 115 therewith and the tie rod connecting the shafts on which the respective anti-friction rollers are mounted.

It will be observed also that the tie rod 31 serves to hold the hollow shafts 26 and 27 against 120 rotation and against longitudinal movement with respect to the members 9 and 10.

Obviously, the present invention is not limited to the precise construction and arrangement shown and described as the same may be variously modified within the scope of the claims annexed hereto.

What I claim as new and desire to cover by Letters Patent is:

1. In a piston, the combination of a plurality of 125 separable aligned end members, means within the periphery thereof for securing the members together, anti-friction means mounted in said members and spaced from each other adjacent the inner ends of said members, and means independent of said securing means for connecting 130 said anti-friction means together for preventing relative displacement thereof.

2. In a piston, the combination of a plurality of 145 aligned end members, means for securing the members together, anti-friction means mounted in the respective members, means positioned between the adjacent ends of said members for varying the distance between adjacent faces of said anti-friction means, and adjustable means inde- 150

pendent of said securing means for connecting said anti-friction means together for preventing relative displacement thereof.

3. In a piston having aligned end portions, the combination of a plurality of shafts mounted in the respective end portions, anti-friction rollers mounted on said shafts, and adjustable means connecting said shafts for securing the shafts and rollers against relative displacement with respect to each other.

4. In a piston having aligned end portions, the combination of a plurality of shafts mounted in the respective end portions, anti-friction rollers mounted on said shafts, and adjustable means directly connected to said shafts adjacent said rollers for securing the shafts and rollers against relative displacement with respect to each other.

5. In a piston having aligned end portions, the combination of a plurality of shafts mounted in the respective end portions, anti-friction rollers mounted on said shafts, a tie rod extending through a portion of said shafts, and means operatively related to the ends of said rod for securing the shafts and rollers against relative displacement with respect to each other.

6. In a piston having aligned end portions, the combination of a plurality of shafts mounted in the respective end portions, anti-friction rollers mounted on said shafts, a tie rod extending through said end portions and said shafts, and means operatively related to the ends of said rod for securing the shafts and rollers against

relative displacement with respect to each other.

7. In a piston having aligned end portions, the combination of a plurality of hollow shafts mounted in the respective end portions, anti-friction rollers mounted on said shafts, a tie rod extending through a portion of said shafts, and means operatively related to the ends of said rod within said shafts for securing the shafts and rollers against relative displacement with respect to each other.

8. In a piston having aligned end portions and bosses associated therewith, the combination of a pair of hollow shafts mounted in the bosses of the respective end portions, anti-friction rollers mounted on said shafts, a tie rod extending through a portion of said bosses and shafts closely adjacent said rollers, and adjustable means operatively related to the ends of said rod within said shafts for securing the shafts and roller against relative displacement with respect to each other.

9. In a piston having aligned end portions, the combination of a pair of hollow shafts mounted in the respective end portions, anti-friction rollers mounted on said shafts, a tie rod extending through a portion of said shafts closely adjacent said rollers, and adjustable means operatively related to the ends of said rod within said shafts for securing the shafts and roller against relative displacement with respect to each other.
